UNITED STATES PATENT OFFICE.

WLADISLAUS ST. MIELCAREK, OF GRAND RAPIDS, MICHIGAN.

FEED-REGULATOR FOR ROLLER-MILLS.

SPECIFICATION forming part of Letters Patent No. 340,898, dated April 27, 1886.

Application filed July 13, 1885. Serial No. 171,551. (No model.)

To all whom it may concern:

Be it known that I, WLADISLAUS ST. MIELCAREK, a citizen of the United States, residing at Grand Rapids, in the county of Kent 5 and State of Michigan, have invented certain new and useful Improvements in Feed-Regulators for Roller-Mills; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 Figure 1 is a view in perspective of the arm J upon the shaft C, showing the end of slotted portion R of said arm in the crank - box K, of the lever O. Fig. 2 is a plan view of Fig. 1, some of the parts being removed to show 20 the crank-pin T. Fig. 3 is a side view of part of the roller-mill, showing the mechanism employed in the application of power to the shaker device. Fig. 4 is a vertical sectional view showing the rear portion of shoe D and 25 shaker mechanism. Fig. 5 is a detail view, and Fig. 6 is a sectional view, on the line z z of Fig. 4.

My invention relates to feed-regulators for roller-mills; and it consists in the improved 30 constructions and combination of parts herein-after fully described, and pointed out in the claims.

Referring to the drawings, I is the shell or case of a mill, having the rollers 1 2 3 4, the 35 shaft of the roller 3 being extended to sustain the pulley 13, which is connected with its companion pulley 12 by the belt 14. Said pulley 12 is carried upon the shaft U, the latter revolving in the journal-box L, which is integral 40 with, and an extension at right angles of, the lever O. Said lever is supported by its fulcrum M, and its power is regulated by the sliding weight N, having a suitable set-screw. The inner end of the shaft U has the pin T at 45 one side of its center, fitting and revolving within the hole S in the block Q. Said block Q slides in grooves P' P in the sides of the slot P in the enlarged portion R of the lever J.

The lever O is provided with a crank-box, 50 K, adapted to be filled with oil, and to receive the end R of the lever J, said crank-box being sufficiently large to permit the free oscillation

of said end R therein when the crank-pin T revolves. The upper end of said lever J is fastened by a set-screw, 15, or otherwise, upon 55 the shaft C, said shaft being extended through to the other side of the case I, and suitably journaled therein. Upon said shaft C, firmly fastened by set-screws 5, are the yokes or spring-supports A A, each member of which 60 has a triple spring composed of the blades a a and the central blade, 7, secured together by the rivet 6. The blades 7 pass through slots in the plates B B, said plates being fastened to the feed-shoes D D. (See Fig. 6.) The 65 feed-shoes are supported at their heels by means of the hangers E, the latter being suspended from the inner ends of the levers 9 9, which pass to the outer side of the case I, through the slots 11, and, turning at right angles, hinge upon suitable fulcrums, and are 70 adjusted by the thumb-screws 10, as shown in Fig. 3. The toes of said shoes are each provided with two supports, F F, arranged upon the inner sides of the shoes, at the corners 75 thereof, and hinged upon the levers G G, having suitable fulcrums, which are adjusted by the thumb-screws H H. (See Fig. 6.)

It will be seen that as the pulleys 12 and 13 revolve, the eccentric motion of the pin T 80 upon the shaft U within the block Q produces a shaking of the lever J, which is communicated through the shaft C to the yokes A A, and the springs terminating the same, thereby causing an oscillating or shaking motion of the plates B B and the feed-shoes connected therewith.

The weighted lever O is the device whereby the tension of the belt 14 upon the pulleys may be regulated, being tight or loose, according 90 to the position of the weight N.

The manner of sustaining the feed - shoes by the supports E and F, regulated by the levers G 9, enables the operator to control the flow of grain. Thus, by lowering the toes so 95 that the incline of the shoes is increased, said shoes feed faster, and by lowering the heels and increasing the distance between the hoppers and the shoes the volume of feed is enlarged.

The hoppers, as shown in Fig. 6, are lettered W.

I claim—

1. In a feed - regulator for roller-mills, the

combination, with a case having hoppers, of shoes arranged below the hoppers, an oscillating shaft, C, yokes A, fitted upon the latter, the springs a, the blades 7, and the plates B, having the slots through which the blades pass, as set forth.

2. In a feed-regulator for roller-mills, the combination, with a case and the hoppers, of shoes located beneath the hoppers and pivotally supported at their outer ends, a shaft, C, means, substantially as described, for connecting the inner ends of the shoes with the latter, the arm J, having slot P, formed with grooves P', the lever O, having a sleeve, L, a shaft, U, having pulley 12, and journaled in the sleeve and formed with an eccentric pin, T, the block Q, to receive the pin, the rollers,

one of which has an extended shaft, and pulley 13, and means, substantially as described, for connecting pulleys 12 and 13, as set forth. 20

3. The combination, with the case and the hoppers, of the shoes arranged below the hoppers, the pivoted levers G, the screws H, the supports pivotally connecting the levers and shoes, the hangers E, the pivoted levers 9, to which the hangers are pivoted, and the thumb-screws 10, for operating the levers 9, as set forth. 25

In testimony whereof I affix my signature in presence of two witnesses.

WLADISLAUS ST. MIELCAREK.
